UNITED STATES PATENT OFFICE

JOSEPH VOGT, OF PEEKSKILL, NEW YORK

RAZOR BLADE HOLDER

Application filed July 21, 1932. Serial No. 623,789.

The invention is a device for holding razor blades so that they may be used as a knife for various purposes and is so arranged that both sides of each edge are continuously held between two clamping members.

The object of the invention is to provide a device for holding razor blades so that the blade may readily be used as a knife.

Another object of the invention is to provide a device for holding razor blades which frictionally holds both sides of the blade continuously at each edge thereof.

Another object of the invention is to provide a device for holding razor blades which has only two parts.

A further object of the invention is to provide a device for holding razor blades which is formed of two pieces of material and so arranged that one piece of material is clamped in the other and the razor blade is clamped between the two pieces of material.

A still further object of the invention is to provide a device for holding razor blades which is provided with means for locating and holding the blade in the proper position.

And a still further object of the invention is to provide a device for holding razor blades which is of a comparatively simple and economical construction.

With these ends in view the invention embodies a back with projections thereon for locating a razor blade and flanges at the edges, and a plate adapted to be frictionally held in said flanges and also adapted to cooperate with a portion of the back to hold a razor blade.

Other features and advantages of the invention will appear from the following description taken in connection with the drawing, wherein:

Figure 1 is a plan view of the device.

Figure 2 is a similar view with the front plate removed.

Figure 3 is a longitudinal section thru the device.

Figure 4 is a cross section thru the handle of the device.

Figure 5 is a similar section thru the blade holding portion of the device.

In the drawing the device is shown as it

would be made wherein numeral 1 indicates the back, numeral 2 the front plate, and numeral 3 a razor blade that may be held between the back and front plate.

The back 1 may be made as shown with a handle portion, as indicated by the numeral 1, and an extension 4 the width of which is slightly less than the width of a razor blade, as indicated by the dotted lines 5 shown in Figure 3. Projections 6 and 7 are formed in the portion 4 and it will be noted that these extend upward and are positioned to correspond with the openings in a razor blade. These projections locate the blade and hold it in the proper position in the device. At the edges of the handle 1 are flanges 8 which are formed as shown in Figure 4 and it will be noted that these flanges are slightly tapered from the point 9, forming the intersection of the handle with the portion 4, to the point 10 at the end of the handle. These edges converge slightly from the point 9 to the point 10 and as the plate 2 is placed in the handle the edges thereof will be frictionally held by the flanges 8 so that the plate will be rigidly held in the handle. The plate 2 is formed, as shown in Figure 1, with a portion to correspond with the handle 1 having slightly tapered edges and an extension 11 to correspond with the extension 4 of the back. The plate 2 may be provided with an opening 12 thru which the projection 7 may extend when the plate is in the position shown in Figure 1 in which it is frictionally held in the flanges 8 and the edges of the extensions 11 are forced against the razor blade thereby forming a positive grip upon the blade. At the opposite end of the plate 2 is a ridge 13 which is formed by pressing a portion of the material upward, as shown in Figure 3, and it will be noted that this ridge may be used to force the plate 2 outward when it is desired to change or remove the blade. It will be noted that the plate 2 is curved upward, as shown in Figure 4, so that it may slide over the projection 7 when it is being removed from or inserted in the handle of the device.

The projections 6 and 7 may be formed by pressing material from the back upward, as

shown in Figure 5, or formed on the back by any other means.

It will be understood that other changes may be made in the construction without departing from the spirit of the invention. One of which changes may be in the shape or general design of the device, another may be in the use of other means for locating the razor blade on the device, another may be in the use of other means for holding one part of the device in relation to the other, and still another may be in the use of other means for holding the razor blade in the device.

15 The construction will be readily understood from the foregoing description. In use the device may be provided as shown and it will be noted that a razor blade may be placed on the projections 6 and 7 and then the plate 20, 2, placed over the blade and the edges thereof passing over the flanges 8 and, as it is forced into place it will frictionally grip and hold the blade against the back. 1. The device may then be used as a kitchen tool or for any 25 other purpose, and it will be noted that as the blade becomes dull it may readily be removed and replaced without removing nuts or screws or without the use of tools of any description. The device therefore provides 30 means for utilizing old razor blades and it makes it possible to hold them in such a manner that the entire blade will be protected and firmly held as it is used.

Having thus fully described the invention 35 what I claim as new and desire to secure by Letters Patent, is:

1. In combination, a back having tapering flanges at the sides and an extension at one end, projections on said extension adapted to 40 hold razor blades, and a front plate having a projection at one end and an opening at the other adapted to receive one of the projections on the back, said front plate adapted to slide into the flanges of the back and be held 45 therein in such a position that it will clamp razor blades to the back.

2. A device for holding razor blades comprising a handle with overlapping flanges at the edges and a flat portion extending 50 from one end said flanges converging toward the outer end, said flat portion having means for locating razor blades thereon, and a curved plate forming a part of said handle also having converging edges corresponding 55 with the flanges of the handle, said plate slideable in and frictionally held in said flanges, said plate having an extending portion corresponding with the extending portion of the handle and adapted to grip and hold razor 60 blades against the extended portion of the handle.

3. A device for holding razor blades comprising a handle with overlapping flanges at the edges and a flat portion extending from 65 one end, said flanges converging toward the

outer end, said flat portion having projections for locating razor blades thereon, and a curved plate forming a part of said handle, also having converging edges corresponding with the flanges of the handle, said plate slideable in and frictionally held in said flanges, 70 said plate having an extending portion corresponding with the extending portion of the handle and adapted to grip and hold razor blades against the extended portion of the handle, said extending portion of the plate having means to snap over the projections of the handle to hold the plate in relation to the handle.

In testimony whereof I affix my signature. 80
JOSEPH VOGT.
